UNITED STATES PATENT OFFICE.

WILLIE ERASTUS STURDAVANT, OF SPRINGFIELD, MISSOURI.

METALLIC CAR-ROOF.

SPECIFICATION forming part of Letters Patent No. 627,151, dated June 20, 1899.

Application filed January 23, 1899. Serial No. 703,207. (No model.)

To all whom it may concern:

Be it known that I, WILLIE ERASTUS STURDAVANT, a citizen of the United States, residing at Springfield, in the county of Greene and State of Missouri, have invented certain new and useful Improvements in Metallic Car-Roofs; and I do hereby declare the following to be a full, clear, and exact description of the invention, such as will enable others skilled in the art to which it appertains to make and use the same.

My invention relates to improvements in metallic car-roofs, the object of which is to provide a cheap, simple, durable, and convenient device to be used as a car-roof and one that is not effected by the bending or twisting of the car while in motion and one that may be removed in sections without taking off the wooden part of the car-roof. This object I attain by means of the device illustrated in the accompanying drawings, forming a part of this specification, in which—

Figure 1 is a vertical cross-section lengthwise of the car. Fig. 2 is a vertical cross-section of the end of the car. Fig. 3 is a detail view showing one of the plates. Fig. 4 is a detail view showing one of the braces or supports for holding the ribs in place.

Similar letters of reference indicate corresponding parts in the several figures.

A is a plate or sheet of metal, made of any suitable material, preferably of galvanized iron, to be used in the roof of a car and is made to enter a groove G² in the side of a ridge-plate G at one end and extends down to the edge or eaves of the car H, just behind the frieze H², which holds it in place and prevents it from slipping out. Said plate A is provided with upturned edges A², which enter the grooves B² in the ribs B. Said plates or sheets A are made of any desired width, preferably to extend from one carline to the other.

B is a rib, made of any desired material, preferably of iron, and is made to enter a groove G² in the side of the ridge-plate G and extend down to the edge or eave of the car, where it is held firmly in place by means of the braces or supports C. Said rib B is made of any desired material, preferably of iron, 50 and is T-shaped, as shown in Fig. 1, and is provided with grooves B² for receiving the flange A² of plate A and has flanges B³, which are provided with holes B⁴ for receiving bolts or securers D for fastening the ribs to the 55 upper covering or framework of the car. Rib B is also provided with an opening B⁵ for receiving the end of the support C, which secures the lower ends of ribs B to the edge of the car. 60

C is a support or brace and is made of any suitable material, preferably of iron, and is made so that one end enters the opening B⁵ in rib B, and the other end is provided with openings C² for receiving screws or bolts for 65 fastening the support to the side of the car. This device allows the plates A to be removed or slipped out by removing the frieze-board H² without disturbing any other part of the roof and also allows the car to bend or twist 70 without tearing or breaking the plates A.

Having thus described my invention, what I claim as new, and desire to secure by Letters Patent, is—

In a car-roof the plate A having upturned 75 edges A² in combination with ribs B provided with grooves B² flanges B³ holes B⁴ and opening B⁵ with a support C, and ridge-pole G, substantially as shown and described.

In testimony whereof I affix my signature 80 in presence of two witnesses.

WILLIE ERASTUS STURDAVANT.
